UNITED STATES PATENT OFFICE

169,147

HANDLE FOR A SAFETY RAZOR

Thomas Lamb, New York, N. Y.

Application November 20, 1952, Serial No. 22,385

Term of patent 14 years

(Cl. D22—3)

To all whom it may concern:

Be it known that I, Thomas Lamb, a citizen of the United States, residing at New York, in the county and State of New York, have invented a new, original, and ornamental Design for a Handle for a Safety Razor, of which the following is a specification, reference being had to the accompanying drawing, forming part thereof.

Figure 1 is a front elevational view of a handle for a safety razor embodying my new design.

Figure 2 is a side elevation of the same.

Figure 3 is a section on the line 3—3 of Figure 1.

Figure 4 is a section on the line 4—4 of Figure 1.

Figure 5 is a section on the line 5—5 of Figure 1.

The conventional portions of the razor head shown in dotted lines in Figures 1 and 2 are only for the purpose of illustration.

I claim:

The ornamental design for a handle for a safety razor, as shown and described.

THOMAS LAMB.
